UNITED STATES PATENT OFFICE

RENÉ DECAUX, OF PARIS, FRANCE, ASSIGNOR TO SOCIETE DES ETABLISSEMENTS GAUMONT, OF PARIS, FRANCE, A CORPORATION OF FRANCE

MOVING PICTURE MACHINE

Application filed May 10, 1929, Serial No. 361,924, and in France May 21, 1928.

My invention relates to moving picture projecting apparatus and its object is to provide an apparatus of that kind, of simple construction and comprising a minimum number of movable organs, making it possible to project thirty-five pictures per second and even more.

According to my invention, the film moves, in a continuous manner, along an arcuate 10 guide, past a window lighted by a luminous source which is combined with a condenser and said film occupies the focal plane of an optical system which sends a beam of parallel rays on a mirror which is caused to oscillate about an axis located in its plane. From that mirror, the luminous rays are directed on to a stationary mirror disposed at 45°, caused to pass through an objective, from which they are projected on the screen. The 20 oscillating movement of the mirror, which is controlled by a cam, is synchronized with the forward movement of the band in such a way that, between successive extinctions produced by a rotary blade acting as a shutter, the image of a determined point on the film is maintained stationary on the screen.

The chief object of my invention is to provide a mechanical arrangement of the parts owing to which the oscillating mirror, the 20 support of said mirror and the control cam for controlling it are caused to cooperate under the best conditions, account being taken of the inertia of the different pieces and of the play which is liable to take place as a consequence of wear and tear. The mirror is fixed on a platform pivoted to a rocking lever of adjustable position and carrying an arm which receives the oscillations of the cam. The mirror bears at three points on the platform and is maintained in place by springs, in such a way as to eliminate all deformation of the reflecting surface.

Other essential particularities of the invention will be obvious from the following description when taken in connection with the accompanying drawings, given by way of example.

In the drawings—

Fig. 1 is a diagrammatic view, partly in

section, showing the general lay-out of my apparatus;

Fig. 2 is a broken section taken along the lines 2^a—2^a and 2^b—2^b of Fig. 3;

Fig. 3 is a longitudinal section of the apparatus taken through the vertical plane 55 passing through the axes of the various optical systems;

Fig. 4 is a plan view showing the gears which connect the driving arm of the cam to 60 the shaft of a toothed cylinder;

Fig. 5 illustrates the arcuate guide;

Fig. 22 is a partial section along the line 22—22 of Fig. 19; 90

Fig. 23 is a diagrammatic section of a film stretching arrangement for preventing sliding.

The general scheme of my apparatus will be first described with reference to Figs. 1, 95 2, 3 and 4.

A designates the luminous source, B a condenser and C the film issuing from the winding spool D, driven by a toothed cylinder E passing beneath a tensioning roller F, over a 100

fixed roller G, over the arcuate guide H, over the toothed cylinder I, then over the toothed cylinder J (at the same time forming a loop between these two cylinders) and, finally, on to the winding spool K.

L is an objective placed at such a distance from guide H, that the surface of film C, when passing in front of the window of the said guide, is in focal plane of said objective, 10 the image of the film thus being formed at infinity. In other words the light rays leaving said objective are parallel and fall against oscillating mirror M, stationary mirror Q, then pass through objective R S having an adjustable focal length, said objective is composed of a converging element R, and a diverging element S, the distance of these two elements determining the position of the focal planes of the system formed by them, so 15 that it is possible to focus said objective on a screen placed at any distance whatever from the apparatus.

Mirror M is supported by a mounting provided with an arm N and it oscillates about point O.

Arm N is urged by a spring T against cam P which, when rotated, gives to the mirror a suitable oscillating movement, that is, a movement such that a luminous ray issuing 20 from a point on the moving film will be stationary after being reflected from movable mirror M.

During the return movement of the mirror to its initial position indicated in dotted lines, a rotary shutter O¹ brings during a suitable time a blade U of cylindrical form across the path of the luminous beam between guide H and objective L. Said blade passes a second time in the field of the optical system 25 producing a second occultation during the projection of the image, and this in order to diminish the scintillation.

The principle of my invention having been outlined, the general construction thereof 30 will now be described. A frame a on which a plate b is fitted, forms a sort of tightly closed box provided with bosses forming the necessary bearings for the shafts that carry the various gears of the moving parts of the apparatus.

These gears are therefore enclosed thus being protected against any cause of deterioration. Moreover one of said gears, indicated at c in Figs. 2 and 3, is in contact with 35 a layer of oil existing at the bottom of the frame a, which bottom consists of two inclined surfaces a¹ a², forming a trough in which the level of oil can be observed through a transparent window a³.

Gear c therefore dips in the oil and projects it over all the movable parts which are thus constantly lubricated, as well as the shafts and the bosses which form the bearings in which said shafts are journaled. The 40 driving shaft controlled through pulley V

actuated as a fly wheel, carries, at the other extremity, cam P and also the driving pinions of the various gear trains which control the shutter and the toothed cylinders E J which serve, respectively, to unwind the upper winding reel and to feed the lower winding reel.

On said driving shaft is keyed a helicoidal pinion d which drives another helicoidal pinion e fixed to a shaft j which carries at another point a helicoidal pinion f meshing with a helicoidal pinion i keyed to the driving shaft of toothed cylinder I.

Two springs r r¹, acting on a thrust ball-bearing l fixed to the extremity of shaft j cause said stop to bear constantly on a cam k integral with a manipulating knob m located outside the apparatus.

When the film, driven by the toothed cylinder actuated by pinions i and f, moves past the window in guide H, the displacement of the mirror under the action of cam P controlled by pinions e and d is such that the image of a point of the band remains stationary between two successive passages of the shutter. There exists, therefore, in this interval of time and for a predetermined adjustment, a definite correspondence between each angular position of the mirror and each position of the film on guide H. In order to modify the relative positions of said elements, it suffices to advance angularly one of the toothed wheels i or d. The problem is solved by displacing shaft j in a longitudinal direction (Fig. 4) by means of cam k, this displacement causing helical pinions i and d to rotate through unequal angles respectively, as the inclination of the threads is not the same in the two pairs of pinions e d and i f. This makes it possible to adjust the position of the film in accordance with the movement of oscillating mirror M, and, consequently, to bring the image projected on the screen in the proper position and in the central part of said screen. The advantage of this device is that it necessitates, between the cam and the driving cylinder, no auxiliary element liable to interfering with the precision necessary to the angular relative positioning of these two elements during their rotation or to cause 50 defects in the stability and clearness of the projection.

The oscillating mirror must be rigorously plane and it is silvered on one of its surfaces which bears on three points 1, 2 and 3 of its support (Figs. 6 and 7). It is applied thereon by two springs R¹ R² (Figs. 8, 9 and 10). Three copper contact studs 1, 2, 3 project slightly from the support and the springs likewise carry copper studs n¹ n² n³ so disposed as to lie exactly opposite the studs of the mirror support in order to avoid any possible deformation of the mirror in spite of the pressure exerted thereon.

The height of boss 3 must be regulated by 55

means of wedges of various thicknesses placed beneath the head of the screw which forms the boss 3 so as to bring the reflecting surface in a position parallel to axis $x-y$ through rotation about 1, 2.

Spring R^1 (Fig. 8), which corresponds to contacts 1 and 2, is provided, at both ends, with lugs 4 and 5 which maintain the mirror and prevent it from sliding in a direction 10 perpendicular to the axis of rotation.

The arm of the mirror support (Figs. 6 and 7) is hollowed out in order to reduce its weight and carries at its extremity on one face a small boss N^1 for maintaining in position 15 the extremity of the spring which applies it on the cam and on the opposite face, i. e., the one in contact with the cam, a projection N^2 , properly rectified, made of hard metal, such as tempered steel, for example, 20 which projection can be secured to the arm by soldering or other means.

In order to facilitate replacement of that piece in case of damage, it is possible to substitute therefor a plate of tempered steel q carrying a lug t^1 engaging a hole in the arm, 25 a notch in which engages another pin t^2 fixed on the arm being adapted to prevent the plate from rotating.

Three small contacts q^1 q^2 q^3 secured to the 30 arm would then allow said plate to be given a well defined position on the arm upon which it is continuously applied by the action of the spring which pushes the arm against the cam. Such an arrangement advantageously 35 replaces an arrangement including a roller and diminishes the wear and tear and the inertia of the moving element.

The distance from the axis of rotation $x-y$ of the oscillating mirror to the axis of the 40 cam must be varied by a small quantity in order to adjust the angle of oscillation of the mirror to the advancement of the film, it being necessary that the linear displacement of said film should be compensated by a suitable 45 angular movement of the mirror. In order to obtain this result by eliminating all possible play between the parts, the axis of the mirror supporting member is supported by two bearings 7 and 8 (Figs. 13, 14 and 15) 50 integral with a member or support 9 pivoted to a shaft 10 fixed on the frame of the apparatus (Fig. 3).

A spring piston 11 (Figs. 16, 17 and 18) is disposed under the extremity of member 9^a 55 so as to cause it to swing about the shaft 10. A stop 13 (Fig. 3) is screwed into another boss fixed to the frame of the apparatus and limits this movement, thus allowing the displacement of axis $x-y$ to the desired extent, 60 without any detrimental play in the mechanism, as the action of said stop limits the play of the shaft in member or support 9, always in the same direction and without loss of time.

65 This arrangement likewise facilitates the

removal of the oscillating mirror support, when the mirror has to be replaced for example.

Cam P (Figs. 2 and 3) fits over the cylindrical extremity of the driving shaft and is 70 fixed to a shoulder X of said shaft by means of a pin and screws allowing an easy mounting and replacing of this member. Said shoulder has substantially the same shape as the cam but is disposed in such a position with respect to said cam that the corresponding bosses lie at an angle of 180° to each other, which very accurately balances the 75 whole of the moving body.

Said cam is surrounded by a casing whose 80 lower part is integral with the frame of the apparatus, the upper part, as well as the surface, being removable for fitting on and removing the cam.

The casing contains a small quantity of oil 85 which comes in contact with the cam through the medium of a wick P^1 carried by a flat spring placed in such a way that one extremity of the wick dips in the oil, the other extremity of said wick being slightly in contact 90 with the cam.

The optical system must be established 95 with great accuracy as the axes of the objectives should be rigorously parallel, and, for this purpose, the whole of the system has been 100 made as a single mechanical unit secured to the frame of the apparatus.

This allows of employing economical machining processes resulting in perfect accuracy. Objectives L and R S, fixed in cylindrical mountings, are completely engaged in corresponding cylindrical recesses, in which they are secured by an encircling clamping element. Guide H (Figs. 3 and 4) adapted 105 to be replaced subsequent to wear due to the passage of the film, is secured to the optical system which serves as a housing for shutter U. It is fixed thereto by means of screws and marking pins which allows of its interchanging.

The condenser, instead of forming a part 110 of the projection lantern, is carried by a rigid mounting provided with an encircling clamp, said mounting being secured to the frame of the apparatus. I thus obtain a very accurate positioning of the condenser, whose optical axis must coincide with that of objective L.

Finally, a platform 50 allows of interposing, between said condenser and the guide, 115 a tank support 51, with or without water circulation, the purpose of which is to intercept, by means of the liquid that it contains, a large proportion of the heat rays of the beam of light before they reach the film.

The mirror support illustrated in Figs. 6 and 7, while excellent from a mechanical point of view, may be rather expensive due to the finish that it requires. Furthermore, its weight (which it is desirable to reduce to a 125 130

minimum) might be too great for certain light apparatus of a known type and might necessitate the use of a powerful return spring and, consequently the application of too high

5 a pressure of the steel plate against the cam.

The mirror support shown in Figs. 19 to 22 composed of two elements, has been so devised as to reduce to a minimum its moment of inertia with respect to the axis of oscillation, which facilitates its working and allows of it being used in light apparatus.

Part 20, which carries shaft x y (Figs. 19 and 21) is made of hard metal turned and milled. Said part carries at 21 a circular 15 shoulder on which is fitted the arm. Said arm is cut out of sheet metal, preferably of a light metal, such as aluminium magnesium, duraluminium, etc. It is secured by means of screws or rivets suitably disposed. Figs. 20 19 and 20 illustrate this member the extremities 22 and 23 of which are bent and perfectly planed. The mirror is applied upon said points by the corresponding springs, said springs being shown in dotted lines at R_1 and 25 R_2 and secured in the same manner as in Figs. 6 and 7. The outline of the mirror is shown by dotted lines M.

The extremity of the arm carries at 24 and 25 two V shaped bosses and also two hooks 30 26 and 27.

Movable plate 30 (Fig. 21), which is made of very hard steel, is apertured at 28 and 29.

Hooks 27 and 28 engage hole 28 and slot 29 respectively.

35 When the arm, pushed by spring T, applies plate 30 against the cam, said cam always contacts the plate along one of its generatrices. The plate is fixed in accurate position by the two supporting hooks without necessitating any special adjustment, whereas the above described mode of positioning by means of three points requires a special preliminary adjustment.

When a plate is worn out, all that is necessary is to slightly remove the lever from the 45 cam, unhook the worn out plate and replace it by a new one, which will fit exactly in the place of the former without necessitating any special adjustment.

50 It has also been noted that due to the difference in the pitches of different films, the unwinding movement of the film driven by the toothed cylinders was not always strictly uniform, this causing a lack in the clearness 55 of projection.

My invention likewise provides means for obviating this disadvantage. Said means consist of a smooth roller and a roller compressor between which the film is engaged before passing over the toothed driving cylinder. This arrangement regularizes the forward motion of the film by preventing the disturbances caused by contact with said driving cylinder from spreading beyond the 65 rollers.

One embodiment of this improvement is illustrated in Fig. 23 which partially reproduces Fig. 1 in a diagrammatical way.

As all the films do not have the same pitch, it follows that when the teeth of cylinder I engage a perforation, they are not always in contact with the edges of said perforation. Said contact is only established when the preceding teeth have left the corresponding perforations and, at this moment a slight sliding of the film on the cylinder takes place. Consequently the movement of the film is not strictly uniform, which results in a lack of clearness of the images projected on the screen.

In order to reduce to a minimum this uneven motion, I interpose between the lower part of frame H and cylinder I a smooth cylindrical roller 31 upon which the film is applied by a rubber covered roller compressor 32 before passing around toothed cylinder I. The position of roller 31 is such that the film, between the base of the guide and toothed cylinder I, forms a broken line the variable curves of which form, due to the elasticity of the film, a sort of spring shock absorber whose action is as follows:

The part of the film included between toothed cylinder E and smooth roller 31 represents a certain mass to which is added that of roller 31. The part of the film included between the smooth roller and driving cylinder I operates as a spring which absorbs the jerks of said driving motion and said jerks are not transmitted to the system comprising, as already stated, the cylinder and the aforesaid portion of the film.

It will be noticed that it is a question of absorbing intermittent sliding of about one or two hundredths of a millimeter at an 105 average rate of one hundred per second. The mass of the smooth cylinder may therefore be chosen very small.

In order to facilitate the mounting of the film said cylinder is very much hollowed out and, consequently, very light, the necessary mass being provided by an auxiliary cylinder keyed on the same shaft and mounted in the body of the apparatus.

It is to be understood that modifications of detail could be made in my above-described device without departing from the spirit of my invention as comprehended within the scope of the appended claims.

Having described my invention what I claim as new and desire to secure by Letters Patent is:

1. In a moving picture projecting apparatus of the type described, the combination of an oscillating mirror, a platform supporting said mirror, three bosses on said platform forming three supporting points for said mirror, flexible means for applying said mirror against said bosses, an arm for transmitting oscillations to said platform, a

cam for transmitting oscillations to said arm, a pivotally mounted support for the platform, and means adapted for adjusting the angular position of said support.

5. 2. In a moving picture projecting apparatus of the type described, the combination of an oscillating mirror, a platform supporting said mirror, three bosses on said platform forming three supporting points for said mirror, flexible means for applying said mirror against said bosses, an arm for transmitting oscillations to said platform, a cam for transmitting oscillations to said arm, two trunnions carried by said platform, a stationary

10 pivotally mounted forked lever, two bearings on said lever for supporting said trunnions and means for regulating the position angularly of said lever whereby the amplitude of said oscillations of said platform 15 and of said oscillating mirror may be varied.

3. In a moving picture projecting apparatus of the type described, the combination of an oscillating mirror, a platform supporting said mirror, three bosses on said platform

20 forming three supporting points for said mirror, flexible means for applying said mirror against said bosses, an arm for transmitting oscillations to said platform, a cam for transmitting oscillations to said arm, two

25 trunnions carried by said platform, a shoulder on one of said trunnions adapted to receive said oscillation transmitting arm, a stationary pivotally mounted forked lever, two bearings on said lever for supporting said

30 trunnions and means for regulating the position angularly of said lever whereby the amplitude of said oscillations of said platform and of said oscillating mirror may be varied.

4. In a moving picture projecting apparatus of the type described, the combination of an oscillating mirror, a platform supporting said mirror, three bosses on said platform forming three supporting points for said mirror, flexible means for applying said mirror

45 against said bosses, an arm for transmitting oscillations to said platform, a cam for transmitting oscillations to said arm, two trunnions carried by said platform, a stationary pivotally mounted forked lever, two bearings

50 on said lever for supporting said trunnions and means including an adjustable stop for regulating the angular position of said lever whereby the amplitude of said oscillations of said platform and of said oscillating mirror

55 may be varied.

5. In a moving picture projecting apparatus of the type described, the combination of an oscillating mirror, a platform supporting said mirror, three bosses on said platform

60 forming three supporting points for said mirror, flexible means for applying said mirror against said bosses, an arm for transmitting oscillations to said platform, a cam for transmitting oscillations to said arm, two trunnions

65 carried by said platform, a shoulder on one

of said trunnions adapted to receive said oscillation transmitting arm, a stationary pivotally mounted forked lever, two bearings on said lever for supporting said trunnions and means including an adjustable stop for regulating the angular position of said lever whereby the amplitude of said oscillations of said platform and of said oscillating mirror may be varied.

6. In a moving picture projecting apparatus of the type described, the combination of an oscillating mirror, a platform supporting said mirror, three bosses on said platform forming three supporting points for said mirror, flexible means for applying said mirror against said bosses, an arm for transmitting oscillations to said platform, a cam for transmitting oscillations to said arm, a plate of hard metal rigidly supported by said arm interposed between said arm and said cam, a pivotally mounted support for the platform, and means adapted for adjusting the angular position of said support.

7. In a moving picture projecting apparatus of the type described, the combination of an oscillating mirror, a platform supporting said mirror, three bosses on said platform forming three supporting points for said mirror, flexible means for applying said mirror against said bosses, an arm for transmitting oscillations to said platform, a cam for transmitting oscillations to said arm, a plate of hard metal rigidly supported by said arm interposed between said arm and said cam, two bosses on said arm forming supporting points for said plate adapted to allow said plate to oscillate and follow the shape of the cam, a pivotally mounted support for the platform, and means adapted for adjusting the angular position of said support.

In testimony whereof I have signed this specification.
